(57) **CLAIM**

The ornamental design for a musical instrument effects pedal, as shown and described.

DESCRIPTION

FIG. 1 is a perspective view of a musical instrument effects pedal showing my new design;

FIG. 2 is a left side elevational view thereof, the right side being a mirror image thereof;

FIG. 3 is a rear elevational view thereof;

FIG. 4 is a front elevational view thereof; and,

FIG. 5 is a top plan view thereof.

The broken lines shown in the drawings are for illustrative purposes only and form no part of the claimed design.
